UNITED STATES PATENT OFFICE.

CLAYTON M. FLORKEY, OF KOKOMO, INDIANA.

VEST-SUPPORTER.

1,384,693.

Specification of Letters Patent. Patented July 12, 1921.

Application filed January 10, 1921. Serial No. 436,185.

To all whom it may concern:

Be it known that I, CLAYTON M. FLORKEY, a citizen of the United States, residing at Kokomo, in the county of Howard and State 5 of Indiana, have invented new and useful Improvements in Vest-Supporters, of which the following is a specification.

This invention relates to a supporter for holding the back of a neck band of a vest 10 in proper place, preventing it from creeping beneath the collar of the wearer and forcing the collar upwardly which causes considerable discomfort to the wearer, and which supporter further holds the portion of a 15 necktie which extends about the collar in place.

An object of the invention is to provide a supporter as specified, which is extremely simple in construction, comprising a single 20 piece stamped from suitable sheet metal and adapted for permanent connection to the neck band of a vest and detachable connection with the rear collar button.

Other objects of the invention will appear 25 in the following detailed description and accompanying drawing wherein:

Figure 1 is a section through a collar, vest, and improved supporter, illustrating the manner of its attachment.

Fig. 2 is a perspective view of the supporter.

Fig. 3 is a plan view of the blank from which the improved vest supporter is formed.

Referring more particularly to the drawings, the improved vest supporter comprises a body 1 stamped from suitable sheet metal and having an attaching portion 2 which is provided with longitudinally extending 40 slits 3 through which the thread, employed for permanently attaching the supporter to the inner surface of the neck of a vest, at the center of the rear thereof, extends. The main body 4 of the supporter extends at right 45 angles to the attaching portion 2, and is bent laterally providing a spacing portion 5 which spaces the collar button engaging portion 6 to one side of the body 4, as clearly shown in the drawings. The collar button engaging

portion 6 is provided with a circular opening 7 which connects, by means of a neck 8, with the opening 9 punched into the body

and which opens out through the lower portion of the collar button engaging portion 6 and extends through the spacing portion 5 and 55 into lateral engaging portion 10 of the body 4 permitting the collar button engaging portion to be slipped downwardly over the rear collar button, to connect the supporter 1 to the collar button for holding the rear portion 60 of the wearer's vest in proper position relative to the collar and coat so as to prevent the vest from getting beneath the lower edge of the collar and pushing it upwardly causing the collar to be uncomfortable as well as 65 unsightly and necessitating the continuous straightening or pulling up of the vest.

The spacing portion 5 also serves to hold the rear portion of the necktie worn by the wearer in proper place preventing it from 70 moving out from beneath the collar.

It is, of course, to be understood that the invention may be constructed in various other manners and the parts associated in other relations and, therefore, I do not desire to 75 be limited in any manner except as set forth in the claims hereunto appended.

Having thus described my invention what I claim is:

1. As a new article of manufacture a vest 80 supporter formed of a single piece of sheet metal and comprising a main body, an attaching portion provided with thread receiving openings to permit attachment of the supporter to a vest, a collar button engaging 85 portion, and a spacing portion connecting said collar button engaging portion to the main body.

2. As a new article of manufacture a vest 90 supporter formed of a single piece of sheet metal and comprising a main body, an attaching portion provided with thread receiving openings to permit attachment of the supporter to a vest, a collar button engaging portion, and a spacing portion connecting 95 said collar button engaging portion to the main body, said main body, spacing portion, collar button engaging portion provided with an opening to permit the mounting of the collar button engaging portion 100 over the collar button.

In testimony whereof I affix my signature.

CLAYTON M. FLORKEY.
